UNITED STATES PATENT OFFICE

149,795

DESIGN FOR A SEWING MACHINE

Norman V. Christensen, Chicago, Ill., assignor to
Union Special Machine Company, Chicago, Ill.,
a corporation of Illinois

Application February 25, 1947, Serial No. 137,167

Term of patent 14 years

(Cl. D70—1)

To all whom it may concern:

Be it known that I, Norman V. Christensen, a citizen of the United States and a resident of Chicago, county of Cook, and State of Illinois, have invented a new, original, and ornamental Design for a Sewing Machine, of which the following is a specification, reference being had to the accompanying drawings, forming a part thereof, in which:

Fig. 1 is a top plan view of a sewing machine, showing my new design;

Fig. 2 is a front elevational view of said sewing machine as viewed in the direction of the arrow 2 in Fig. 1; and

Fig. 3 is a side elevational view of said sewing machine as viewed in the direction of the arrow 3 in Fig. 1.

I claim:

The ornamental design for a sewing machine, as shown.

NORMAN V. CHRISTENSEN.
